Inventor
HARRY S. TOOKER

UNITED STATES PATENT OFFICE.

HARRY S. TOOKER, OF JOPLIN, MISSOURI, ASSIGNOR TO WILLIAM D. JAMES, OF KANSAS CITY, MISSOURI.

PUMP.

Application filed December 6, 1924. Serial No. 754,417.

This invention relates to pumps, and is an improvement over the construction shown in my prior Patent No. 1,400,188, granted December 13, 1921.

In my prior patent, I have shown a pump in which a moving element or drive member is adapted to reciprocate a piston or pistons arranged in cylinders and connected to a pair of water columns whereby power may be transmitted through the columns of water to a pump cylinder arranged at a distance from the source of power, such as, for instance, at the bottom of a mine shaft.

An object of the invention is the provision of an improved construction in a pump of this character that is compact in form and easily handled.

A further object is the provision of regulating means whereby the speed of the flow of water may be regulated to agree with the speed of the jack.

A further object is the provision of a pump of this character which may be operated in a suspended position above the water level or in a submerged position.

In the accompanying drawings, I have shown one embodiment of this invention. In this showing:

Figure 1 is a plan view of the cylinder connected to the prime mover or jack and its associated parts,

Figure 2 is a side elevation of the pump cylinder adapted to be mounted in the mine shaft,

Figure 3 is a transverse vertical sectional view on line 3—3 of Figure 1,

Figure 4 is a vertical sectional view of the pump cylinder,

Figure 5 is a transverse sectional view on line 5—5 of Figure 4, and,

Figure 6 is a plan view of the pump cylinder with the cover of the valve chest and the valves removed.

Referring to the drawings, the reference numeral 1 designates generally a source of power which may be of any type of prime mover. A connecting rod 2 is adapted to be reciprocated by the prime mover, and this connecting rod is connected to a piston (not shown) arranged in a cylinder 3. The cylinder is provided with outlets 4 at opposite ends, which are adapted to be connected to pipes 5 extending downwardly, forming a pair of water columns.

Referring to Figure 3 of the drawings, the ends of the cylinder are connected to pipes 4', extending upwardly and communicating with a T 5'. Valve casings 6 are arranged in horizontal arms 7 and these valve casings are provided with check valves 8, which permit flow of water to the pipes 4' but prevent it from flowing in a reverse direction. The T is connected to a vertical pipe 9, communicating with a reservoir 10. The pipes 4' are further provided with relief valves 11, having suitable handles 12 to permit manual operation.

On one side of the cylinder, there is provided a pair of pipes 13 (see Figure 1), connected to elbows 14. These elbows are connected to a transverse pipe 15, and a T-joint 16 is arranged intermediate the ends of the pipe 15. Check valves 17 are arranged in this pipe to permit flow of water inwardly to the T-joint 16. The pipe 15 is connected outwardly of each check valve to a pipe 18 and these pipes are connected to elbows 19, which are in turn connected to each other by a horizontal pipe 20. Intermediate the ends of the pipe, there is provided an equalizing valve 21 normally held in closed position by a spring (not shown) but which is actuated automatically by a difference in pressure in the pipes 18 and the casing of the valve is connected to the T-joint by a pipe 22. Outwardly opening check valves 23 are arranged on each side of the valve 21. Beneath the elbows 14, the pipes 13 are provided with T-joints 24, connected to a transverse pipe 25, and this pipe is provided with a manually operable valve 26.

A pump 27 is connected to the lower ends of the vertical pipes 5. As shown, the pump comprises a power cylinder 28 and a pump cylinder 29. The power cylinder is provided with openings 30 at each end, adapted to receive connecting members 31, which are connected to the lower ends of the water columns and a piston 32 is arranged therein. A partition 33 separates the power cylinder from the pump cylinder and the piston is provided with a piston rod 34, passing through this partition. As shown, a suitable packing 35 may be provided in the partition to receive the piston rod and prevent leakage. A coil spring 36 is secured to one end of the cylinder and this

spring is adapted to be engaged by the piston to take up end thrust.

The pump cylinder is provided with a piston 37 mounted on the other end of the piston rod 34, and adapted to be moved by the piston rod. The outer end of the pump cylinder is also provided with a spring 36 adapted to be engaged by the piston 37 to take up end thrust when the pistons are traveling in the opposite direction. Above the cylinder, the pump is provided with a pair of pump chambers 38, separated from each other by a partition 39 and connected to the opposite ends of the pump cylinder by passages 40. An inlet chamber 41 is arranged beneath the pump chambers and communicates with an inlet pipe 42. The pump chamber and the inlet chamber are separated from each other by a horizontal wall 43, and this wall is provided with a plurality of valve openings 44. Each of these openings is provided with a transverse member 45, having a central opening 46 for the reception of a valve stem 47. A valve 48 of the disk type is arranged on the lower end of each valve stem and is normally retained on its seat by a spring 49. The valves are adapted to open inwardly by suction existing within the pump chamber. The pump is further provided with an outlet chamber 50, separated from the pump chambers by a horizontal wall 51, and a vertical wall 52. The horizontal wall is provided with a plurality of openings 53 having transverse members 54. These transverse members are provided with openings 55, adapted to receive valve stems 56. Disk valves 57 are mounted on these stems and are normally retained in closed position by means of springs 58. These valves are adapted to be opened by pressure within the pump chambers. The outlet chamber communicates with an outlet pipe 59.

In operation, the cylinder 27 is first located in the mine and the columns 5 attached. The pet cocks 11 are opened and water is supplied to the reservoir 10 until the system is filled. When water begins flowing from the pet cocks, so that all air has been expelled, the pet cocks are closed and the reservoir is filled with water. The prime mover is started to actuate the piston in the cylinder 3 and movement of the piston alternately causes an increase and decrease in pressure in the columns 5. This change of pressure reciprocates the piston 32 in the power cylinder 28 and the piston 37 likewise reciprocates, being connected to the piston rod 34. The springs 36 on the opposite ends of the cylinders are engaged by the pistons to prevent end thrust. When the piston 37 reciprocates in the pump cylinder, the pump acts in the same manner as an ordinary double-acting suction pump. The transverse wall 39 forms a pair of pump

chambers and as the piston moves away from either end of the cylinder, a partial vacuum is created in the pump chamber through the passage 40. This opens the inlet valves 48, admitting water from the inlet chamber 41. The return movement of the piston creates a pressure in the pump chamber and the outlet valves 57 are opened to deliver the fluid to the outlet pipe 59. The inlet and outlet chambers 41 and 50 both extend the full length of the two pump chambers.

During the operation of the device, the reservoir is maintained full of water and any decrease in the supply of water in either column is compensated for from the reservoir. The check valves 8 prevent the water from returning to the reservoir when pressure is built up in either of the columns. The regulating mechanism arranged on one side of the cylinder permits the stroke of the piston to be regulated according to the stroke of the jack. The valve 21 is employed for this purpose. The pipe connection 25 and the valve 26 are employed when starting the device at a high rate of speed, the valve 26 being opened and slowly closed to act as a clutch to secure the proper regulating action through the regulating system.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In a device of the character described, a cylinder, fluid pressure conveyors connected to the opposite ends of said cylinder, a reservoir connected to the opposite ends of said cylinder, a regulator connected to the opposite ends of said cylinder, said regulator comprising conduits connected to the ends of the cylinder, a transverse conduit connected thereto, an equalizing valve arranged in said transverse conduit, and check valves arranged in said transverse conduit on each side of said equalizing valve.

2. In a device of the character described, a cylinder, a piston arranged in said cylinder, an inlet chamber arranged on one side of said cylinder and extending substantially throughout its entire length, a pair of pump chambers communicating with said inlet chamber, a wall separating said pump chambers from said inlet chamber, said pump chambers communicating with the ends of said cylinder, valves arranged in said wall to permit the passage of fluid from said inlet chamber to said pump chambers, an outlet chamber extending substantially the entire length of said cylinder, a wall separating said outlet chamber from said pump chambers.

bers, and valves arranged in said wall to permit passage of fluid from said pump chambers to said outlet chamber.

3. In a device of the character described, 5 a cylinder, fluid pressure conveyors connected to the opposite ends of said cylinder, a reservoir connected to the opposite end of said cylinder, a pipe connected to each end of said cylinder, a pair of transverse pipes 10 connected at their ends to said first named pipes, a pair of inwardly opening check valves arranged in one of said transverse

pipes, a pair of outwardly opening check valves arranged in the other of said transverse pipes, and a branch pipe connected at 15 each end to one of said transverse pipes between the check valves arranged therein.

4. A device constructed in accordance with claim 3 provided with a manually controlled valve arranged in one of said transverse 20 pipes.

In testimony whereof, I affix my signature:

HARRY S. TOOKER.
